United States Patent Office

Des. 194,533

Patented Feb. 12, 1963

194,533

COPING TILE CORNER

Kingsley C. Sopp, Pomona, Calif., assignor to Pomona Tile Manufacturing Company, Los Angeles, Calif., a corporation of California

Filed July 20, 1961, Ser. No. 65,987

Term of patent 14 years

(Cl. D18—2)

FIG. 1.

FIG. 2.

FIG. 3.

FIG. 4.

FIG. 6.

FIG. 5.

I claim:

The ornamental design for a coping tile corner, as shown.
